DESIGN FOR AN EXPANSIBLE LINK CHAIN FOR WATCH BRACELET OR THE LIKE

Edwin F. M. Speidel, Cranston, R. I.

Application August 17, 1944, Serial No 114,908

Term of patent 14 years

(Cl D45—4)

To all whom it may concern:

Be it known that I, Edwin F. M. Speidel, a citizen of the United States residing at Cranston, in the county of Providence and State of Rhode Island, have invented a new, original, and ornamental Design for Expansible Link Chain for Watch Bracelets, or the Like, of which the following is a specification, reference being had to the accompanying drawing, forming part thereof.

In the drawing,

Fig. 1 is a top plan view of an expansible link

chain for watch bracelets or the like, showing my new design;

Fig. 2 is a top plan view thereof in an extended position; and

Fig. 3 is a side view of one of the links of the expansible link chain.

I claim:

The ornamental design for an expansible link chain for watch bracelets or the like, substantially as shown.

EDWIN F. M. SPEIDEL.
